HINGE

Charles F. Lutz, Milwaukee, Wis.

Application March 23, 1931. Serial No. 524,592

1 Claim. (Cl. 16—176)

The present invention relates in general to an improved hinge structure, and relates more specifically to improvements in the construction and operation of a detachable hinge which is especially applicable to swinging windows, doors or the like.

Generally stated, an object of the invention is to provide an improved hinge which is simple in construction and efficient in operation.

10 Some of the more specific objects of the invention are as follows:

To provide an improved hinge structure which is especially applicable to swinging windows, doors or similar closures.

15 To provide a hinge construction wherein the fixed and movable elements may be readily and quickly detached or assembled.

To provide a hinge which is light but strong in construction, and all parts of which may be 20 manufactured at minimum cost.

To provide a hinge assemblage, the various elements of which are interchangeable with similar parts of other assemblages, and which may be conveniently applied to a swinging closure and 25 its supporting frame.

To provide a hinge structure which is compact in construction, and which presents a neat and pleasing appearance.

To provide improved mechanism cooperable 30 with a hinge supported closure, for maintaining the hinge and closure in various positions of adjustment.

These and other objects and advantages will be apparent from the following detailed description.

35 A clear conception of several embodiments of the invention and of the mode of constructing and of manipulating hinge structures in accordance therewith, may be had by referring to the drawing accompanying and forming a part of this specification, in which like reference characters designate the same or similar parts in the various views.

Fig. 1 is an outside view of a storm window 40 or screen, having a set of the improved hinges applied to one side thereof;

Fig. 2 is a vertical section through the assemblage of Fig. 1, the section being taken on the line 2—2 of Fig. 1 and the hinges having been omitted;

Fig. 3 is a part sectional top view of the assemblage shown in Fig. 1, the section being taken along the line 3—3 of Fig. 1;

Fig. 4 is a part sectional enlarged view of a 55 fragment of the assemblage of Fig. 1, showing the

details of construction of one of the improved hinges;

Fig. 5 is a similarly enlarged vertical section through the fragment and hinge of Fig. 4, the section being taken along the line 5—5 of Fig. 4;

Fig. 6 is an enlarged inside view of a fragment of the assemblage of Fig. 1, showing the details of construction of the closure latch, the view being taken on the line 6—6 of Fig. 2;

Fig. 7 is a further enlarged horizontal section 65 through the latch structure of Fig. 6, the section being taken along the line 7—7 of Fig. 6; and

Fig. 8 is a fragment of a window and supporting casing, showing a modified construction used as a window hanger.

Referring to Figs. 1 to 7 inclusive of the drawing the improved hinge has been shown as applied to the side of an ordinary casement window or screen in order to swingably support the same.

Each of the improved hinges comprises in general 70 a bracket 10 adapted for attachment to the casing 11 by means of screws 12 or the like; a hinge element 13 adapted for attachment to the screen or window frame 14 by means of screws 15 and having

a tubular portion 16 provided with end openings which are alinable with sockets 17 formed in the bracket 10; and an axially movable pivot 18 disposed within the tubular portion 16 of the element 13 and having end portions movable into the sockets 17 of the bracket 10 to form a hinge 85 connection between the bracket 10 and the element 13. Each pivot 18 is resiliently restrained against movement within the tubular portion 16, by means of a leaf spring 19, and is provided with a lateral recess 20 adapted to receive the swinging end of an arm 21. Each of the arms 21 is attached to the outer end of a pivot pin 22 by means of a clamping screw 23, and the pivot pin 22 is rotatably supported in a bore in the frame 14 and has its inner end provided with an adjusting 90 handle 24.

In the horizontally swingable casement type of window, it is preferable to utilize two or more of the improved hinges associated with one of the side edges of the closure, and the opposite edge 100

of the window frame may be provided with a locking or holding latch associated with the inside of the frame and casing, as shown in Figs. 1, 2, 3, 6 and 7. This latch comprises a latch bar 25 swingably supported upon the frame 14 by

means of a pivot bracket 26 and having an integral tongue 27 adapted to engage the adjacent portion of the casing 11 to retain the window in closed position as shown in Figs. 6 and 7. The swinging portion of the bar 25 has a through 105

opening 28 cooperable with a spring clip 29 in order to retain the bar 25 in locking position. The edge of the bar 25 may also be provided with one or more notches 30 which are engageable with a 5 grooved stop pin 31 secured to the casing 11, when the window is swung open and the latch bar 25 is disposed horizontally, as shown in Figs. 2 and 3, to thereby hold the window open to any desired extent.

10 In the modified form of hinge or hanger shown in Fig. 8, the bracket 32 is of single construction and is secured to the casing 11 above the window frame 14. The hinge element 13 and the parts associated therewith are identical with the corresponding structure previously described, and this modified device can be used advantageously in place of the ordinary storm window and screen hangers which present numerous obstacles when it is attempted to hang such closures from the 20 inside.

In order to assemble a frame 14 and casing 11 having the improved hinges applied thereto, it is only necessary to set the pivots 18 by manipulation of the handles 24, so that the ends of the 25 pivots do not project from the ends of the tubular portions 16 of the confining elements 13. The springs 19 will retain the pivots 18 within the tubular portions 16 until the frame 14 is positioned within the opening in the casing 11 with 30 the openings of the tubular portions 16 in alignment with the sockets 17 of the adjacent brackets 10. The handles 24 may then be manipulated to move the pivots 18 axially within the tubular portions 16 until the pivot ends enter the adjacent 35 sockets, as shown in Figs. 1, 4 and 8, thereby completing the hinge connections. The windows or screens may be subsequently swung about the pins 18 as pivots, and with the latch applied, may be retained in open or closed position. The hinge 40 connection may obviously be readily released by manipulating the handles 24 from within the enclosure, and these handles may be set at any desired position relative to the arms 21 by means of the clamping screws 23.

45 It will thus be noted that the invention provides a simple, compact and highly efficient hinge and latch structure which may be readily applied and manipulated. The brackets 10, 26, 32, the elements 13, the latch bars 25 and the spring 50 clips 29 may be readily formed of sheet metal with the aid of punches and dies, thereby reduc-

ing the cost of construction thereof to a minimum and permitting interchangeability of these parts. While the pivots 18 when used in connection with the double brackets 10, may be shifted axially in either direction in order to complete the hinge 80 connection, the double brackets 10 may be replaced by single brackets 32 whenever desired. The improved latch mechanism may or may not be used in conjunction with the improved hinge structure and has been found extremely effective 85 in actual use.

It will be noted that the angular disposition of the bracket 26 which supports the latch bar 25, causes this bar to swing clear of the casing when the bar is swung about its pivot, thereby avoiding 90 obstruction to the opening and closing of the window or screen frame 14. The latch bar 25, however, serves to effectively retain the window or screen in closed position when the end of the bar has been brought into locking engagement with the clip 29. The formation of this 95 latch bar and the pivotal mounting thereof, constitute an important feature of the present invention.

It should be understood that it is not desired to 100 limit the invention to the exact details of construction herein shown and described, for various modifications within the scope of the claim may occur to persons skilled in the art.

It is claimed and desired to secure by Letters 105 Patent:

In combination, a socketed bracket and an element formed for attachment respectively to the exterior of a one-piece cooperating casing and window frame, a pivot carried by said element and 110 cooperable with the socket of said bracket to form a hinge connection between the casing and frame, and an arm having one end operatively connected with said pivot and having its other end extended rotatably through the frame and 115 shaped to provide a lifting handle on the inside of said frame, said handle having a part spaced a sufficient distance from the frame to provide for insertion of the fingers between the handle and frame when the frame is being lifted into 120 position and the handle being turnable without changing the position of the fingers to operate the pivot to move the latter into and out of the socket.
